UNITED STATES PATENT OFFICE.

JOHN W. JAMES, OF SALT LAKE CITY, UTAH.

SLED-BRAKE.

SPECIFICATION forming part of Letters Patent No. 624,498, dated May 9, 1899.

Application filed February 8, 1899. Serial No. 704,955. (No model.)

To all whom it may concern:

Be it known that I, JOHN W. JAMES, a resident of Salt Lake City, in the county of Salt Lake and State of Utah, have invented certain new and useful Improvements in Sled-Brakes; and I do hereby declare the following to be a full, clear, and exact description of the invention, such as will enable others skilled in the art to which it appertains to make and use the same.

My invention relates to an improvement in sled-brakes, the object of the invention being to provide a brake which can be operated to either slacken or stop the forward or rearward movement of a sled.

A further object is to so construct a brake for a sled that a great leverage will be secured to drive the brake-shoe into the snow or ice to stop the sled.

20 A further object is to provide a brake for sleds which will be simple in construction, cheap to manufacture, easy to operate, and require a minimum amount of power to operate it.

25 With these objects in view the invention consists in certain novel features of construction and combinations and arrangements of parts, as will be more fully hereinafter described, and pointed out in the claims.

30 In the accompanying drawings, Figure 1 is a perspective view of my improved sled, showing the brake secured thereto; and Fig. 2 is a view in section.

1 represents an ordinary bob-sled, comprising the runners 2 and the body 3, supported thereon. When two bobs are employed, I prefer to use my brake on the rear bob. A shaft 4 is revolvably mounted in suitable bearings secured to the bolster 5 or to the under 40 side of the platform or body, if desired. One end of the shaft 4 is bent upward to form a lever 7, having a hole or opening near its end for the reception of a rod 8, which connects the same with a suitable operating-lever 9.

45 Any suitable rack 10 may be provided for said operating-lever, whereby to secure the same at any adjustment desired, or, if desired, I may provide rings or loops a on the lever 7 for the reception of a pole or rod b for 50 operating same. This form of operating-lever is employed when no body is used.

The shaft 4 is provided between its ends

with arms 11, which are pivotally connected at their ends to the bifurcated rear ends of rods or pitmen 12. The rods or pitmen 12 project forwardly from the crank-arms 11 and are bifurcated at their forward ends for attachment to my improved brake-shoes 13. The brake-shoes 13 are made similar in general contour and are disposed one on each side of each runner and pivoted to said runners by means of suitable pins or bolts 14, as shown. Washers 14^a are disposed between the brake-shoes and runners whereby to prevent wear on the latter.

It will be seen from the above description that when it is desired to stop or slacken the speed of a sled the lever 9 is pushed forward, thus pulling the rod 8 and lever 7, which operation will turn the shaft 4 and move the arms 11 thereon in a rearward direction, thus pulling the rods 12 and the upper ends of the brake-shoes 13 and forcing the ends of the shoes into the snow and checking the momentum of the sled.

55 By the particular construction and arrangement of parts above described I secure a great leverage on the shoes, and hence am enabled to drive them deep into the snow and maintain them in such position with slight exertion on the part of the operator.

70 Each brake-shoe is made hook-shaped in general form, with the curved portion a' (which constitutes the long arm of the lever) terminating approximately over the pivotal connection of the shoe to the runner, and the lower end of each shoe (which constitutes the short arm of the lever) is curved slightly downwardly, and it forms a tooth at b. It will 75 also be observed that the free ends or short arms of the brake shoes or levers can be readily made to assume positions at right angles to the runners, and thus serve to positively resist the progress of the sled as contradistinguished from the partial or limited 80 resistance offered by the shoes rubbing on the snow when the free ends of said shoes are disposed at an obtuse angle to the runners. The amount of resistance which the rider 85 wishes to offer to the progress of the sled is 90 therefore completely within his control.

95 Various slight changes might be resorted to in the general form and arrangement of the several parts described without departing

from the spirit and scope of my invention, and hence I would have it understood that I do not wish to limit myself to the precise details set forth, but consider myself at liberty 5 to make such slight changes and alterations as fairly fall within the spirit and scope of my invention.

Having fully described my invention, what I claim as new, and desire to secure by Letters 10 Patent, is—

1. The combination with a sled and a crank-shaft mounted thereon, of a hook-shaped brake-shoe pivotally attached near one end to the sled-runner at a point forwardly of the

15 crank-shaft, the hooked end of said shoe projecting forwardly and then rearwardly, and terminating over the pivoted attachment of the shoe to the runner, and a rod connecting the extremity of said hooked end of the shoe

20 with the crank-shaft, whereby when said crank-shaft is operated in one direction, the

rod will pull upon the shoe and turn it on its fulcrum to project its shorter arm or member below the lower face of the runner.

2. The combination with a sled and a crank- 25 shaft mounted thereon, of a brake-shoe pivotally connected near its rear end to the runner of the sled at a point in advance of the crank-shaft, said rear end of the shoe being substantially at right angles to the shoe at 30 its pivotal support, the portion of the shoe forwardly of its pivotal support being curved and projected rearwardly and a rod connecting the extremity of said curved portion with the crank-shaft. 35

In testimony whereof I have signed this specification in the presence of two subscribing witnesses.

JOHN W. JAMES.
